(57) **CLAIM**

The ornamental design for an amp/power conditioner 3 oval display, as shown and described.

DESCRIPTION

A portion of the disclosure of this design patent document contains material to which a claim of copyright protection is made. The copyright owner has no objection to the facsimile reproduction of the patent document or the patent disclosure as it appears in the U.S. Patent and Trademark office file or records, but reserves all other copyright rights.

FIG. 1 is a perspective view of an Amp/Power Conditioner 3 oval display, in accordance with the present invention.

FIG. 2 is a front view of an Amp/Power Conditioner 3 Oval Display, in accordance with the present invention.

FIG. 3 is a top view of an Amp/Power Conditioner 3 Oval Display, in accordance with the present invention.

FIG. 4 is a rear elevation of an Amp/Power Conditioner 3 Oval Display, in accordance with the present invention.

FIG. 5 is a bottom view of an Amp/Power Conditioner 3 Oval Display, in accordance with the present invention.

FIG. 6 is a left side view of an Amp/Power Conditioner 3 Oval Display, in accordance with the present invention.

FIG. 7 is a right side view of an Amp/Power Conditioner 3 Oval Display, in accordance with the present invention.

FIG. 8 is a perspective view of FIG. 1 showing an alternative arrangement of environment of an Amp/Power Conditioner 3 oval Display, in accordance with the present invention.

FIG. 9 is a front view of FIG. 2 showing an alternative arrangement of environment of an Amp/Power Conditioner 3 Oval Display, in accordance with the present invention.

FIG. 10 is a rear elevation of FIG. 4 showing an alternate arrangement of environment of an Amp/Power Conditioner 3 Oval Display, in accordance with the present invention.

The broken lines showing the environment in FIGS. 1-10 are for illustrative purposes only and form no part of the claimed design.
